FIG. 5.

FIG. 7.

→ FIG. 6.

FIG. 8

A diagram of a bone structure. It has a central horizontal slot with a T-shaped cross-section. At each end of the slot, there is a circular depression. The top circular depression is labeled '38' on both its left and right sides. The bottom circular depression is labeled '39' on both its left and right sides. Above the central slot, the number '36' is written with a downward-pointing arrow. Below the central slot, the number '37' is written with an upward-pointing arrow.

DEVICE FOR PACKAGING LAUNDRY

Walter C. Krout, Charlotte, N. C.

Original application July 18, 1936, Serial No. 91,400. Divided and this application March 27, 1937, Serial No. 133,457

3 Claims. (Cl. 223—83)

My invention consists in a new and useful improvement in devices for packaging laundry and is designed more particularly for packaging men's shirts having starched collars, freshly laundered. 5 This application is a divisional application from my original application, Serial Number 91,400, filed on July 18, 1936, patented April 6, 1937, Number 2,076,467. Within comparatively recent times, the practice has been adopted by many 10 laundries of starching collars attached to men's shirts, and in packaging shirts so laundered the pressure incident to the packaging tends to crush such starched collars. My improved device obviates the possibility of such damage and permits 15 packaging of a considerable number of such shirts, insuring ample protection to the collars. The particularly novel feature of my device is that it provides spacers applied to the collars of the shirts by insertion within the collars and 20 folds thereof, so as to be interposed between the shirts, by which any pressure due to packaging is sustained by the shirts and spacers, and is not exerted upon the collars. I consider the details 25 of construction of my improved supporting elements which serve as spacers constitute a novel and useful improvement.

While I have illustrated in the drawings filed herewith and have hereinafter fully described several specific embodiments of my invention, it 30 is to be distinctly understood that I do not consider my invention limited to said specific embodiments, but refer for its scope to the claims appended hereto.

In the drawings:

35 Fig. 1 is a vertical section of a package containing two shirts, illustrating the use of my improved device.

Fig. 2 is a fragmentary top plan view of a shirt provided with my improved device.

40 Fig. 3 is a front elevation of my improved device, illustrating it in the position shown in Fig. 2.

Fig. 4 is a top plan view of my improved device.

45 Fig. 5 is a vertical longitudinal section through the upper portion of a shirt provided with a modified form of my device.

Fig. 6 is a top plan view of the two parts of the modified form of my device illustrated in Fig. 5.

Fig. 7 is a vertical longitudinal section through the upper portion of a shirt provided with another modified form of my device.

50 Fig. 8 is a top plan view of two parts of the modified form of the device illustrated in Fig. 7.

Fig. 9 is a bottom plan view of the fastening means employed in the modified form of the device illustrated in Figs. 7 and 8.

As illustrated in Fig. 4, my improved device comprises a member 1 having the lower concave 5 edge 2 and the upper convex edges 3 and 4, parallel with the edge 2 and extending from the ends 5 to the edges 6 and 7 respectively, forming the tongue 8 having the score 9 connecting the inner ends of the edges 6 and 7, and a second score 10 parallel with the score 9 and disposed about midway between the score 9 and the upper ends of the edges 6 and 7. Formed integral with the tongue 8 is the member 11 having the concave edges 12 and 13 extending 10 outwardly from the tongue 8 and adjacent to the edges 3 and 4 respectively of the member 1. The member 11 has the outer convex edge 14 parallel 15 with the edge 2 and edges 3, 4, 12 and 13. The member 11 has the obtuse-angled ends 15 forming points 16.

As illustrated in Fig. 2, when my improved device is applied to the collar C of the shirt S, the member 1 curving to conform to the curvature of the collar C fits against the inner face of the 25 inner wall of the collar C, and the tongue 8 being folded on the score 9, its portion 8' projects forwardly from the member 1 through the front opening of the collar C. The tongue 8 being bent on the score 10, its portion 8' extends downwardly and forwardly, the member 11 being inserted beneath the wings W of the collar C, the points 16 facilitating such insertion, and the member 11, when so inserted curving to conform 30 to the curvature of the collar C, bearing 35 against the outer face of the inner wall of the collar C, co-acts with the member 1 to clasp the inner wall of the collar C, therebetween. As clearly illustrated in Fig. 3, the bending of the tongue 8, on the score 9, away from the member 1, when my device is positioned as indicated in Fig. 2, provides the abutments 17 at the inner 40 ends of the edges 3 and 4 of the member 1. It is to be particularly noted (see Fig. 1) that by reason of the disposition of the device, as above 45 described, the edges 3 and 4 with these abutments 17 are positioned at a considerable distance beyond the top edge C' of the collar C, thus effectually providing the spacing element for the shirt S. It is, therefore, obvious from 50 the illustration of the use of my improved device in Fig. 1 that when a pair of shirts S, each properly provided with one of my improved spacing devices, are faced and enclosed in a suitable box B, the lower portion S' of each shirt, posi- 55

tioned adjacent the collar C of the other shirt S, is supported by my improved spacing device, in such a way as to prevent its contact with the collar C.

5 The modified form of device, illustrated in Figs. 5 and 6, comprises the rectangular member 21 having the notch 22, and the arcuate member 23 having the tongue 24 provided with the scores 25 and 26. It is to be noted that the 10 width of the notch 22, at its outer end, is the same as the width of the tongue 24, and slightly greater at its inner end.

As illustrated in Fig. 5, the member 21 curving to conform to the curvature of the collar C 15 fits against the inner face of the inner wall of the collar C. The member 23 is inserted beneath the wings W of the collar C, and when so inserted curving to conform to the curvature of the collar C, it bears against the outer face of the inner wall of the collar C, and the tongue 24 of the member 23 being folded on the score 25 projects rearwardly from the member 23 through the front opening of the collar C and is received through the notch 22 of the member 21, and being again bent on the score 26 extends 20 downwardly and is folded against the inner face of the member 21, the members 21 and 23 co-acting to clasp the inner wall of the collar C therebetween.

30 It will be noted from Fig. 5 that when the parts are positioned as above described, the tongue 24 is positioned at the bottom of the notch 22 and that the upper edge 21' of the member 21 is disposed at a considerable distance beyond the 35 top edge C' of the collar C. Thus it is obvious that by the use of this modified form of my device, I secure the same result as by the use of that form of my device illustrated in Fig. 1, viz. a spacing element to prevent contact of the lower portion S' of the shirt S with the collar C.

40 The modified form of device illustrated in Figs. 7, 8 and 9 comprises the rectangular member 31 having the notch 32 and circular orifice 33, and the arcuate member 34 having the orifice 35, and the clamping element 36 having the shank 31 and plates 38 with fangs 39.

As illustrated in Fig. 7, the member 31 curving to conform to the curvature of the collar C fits 50 against the inner face of the inner wall of the collar C. The member 34 is inserted beneath

the wings W of the collar C, and when so inserted curving to conform to the curvature of the collar C it bears against the outer face of the inner wall of the collar C. The shank 31 of the clamping element 36 is passed downwardly 5 through the notch 32 of the member 31, and the plates 38 are bent downwardly and inwardly, their fangs 39 passing through the orifices 33 and 35 and piercing the meeting edges of the inner wall of the collar C, the clamping element 36 10 bearing against the members 31 and 34 causing them to clasp the inner wall of the collar C therebetween.

15 It will be noted from Fig. 7 that when the parts are positioned as above described, the clamping element 36 is in the notch 32, and that the upper edge 31' of the member 31 is disposed at a considerable distance beyond the top edge C' of the collar C. Thus it is obvious that by the use of the modified form of my device illustrated in 20 Figs. 7, 8 and 9, I secure the same result as by the use of the other forms of my device heretofore described, viz. a spacing element to prevent contact of the lower portion S' of the shirt S with the collar C.

25 Having described my invention, what I claim is:

1. In a spacing element for use in packaging shirts, the combination of a band for insertion within the fold of the shirt collar; a second band for insertion within the collar provided with a 30 notch; and a third band passed through said notch and connecting said first and second bands.

2. In a spacing element for use in packaging shirts, the combination of a band for insertion into the fold of the shirt collar, said band having 35 an orifice; a second band for insertion within the collar, said second band having an orifice; and a clamping element having fangs adapted to pass through said orifices and pierce the shirt collar.

3. In a spacing element for use in packaging shirts, the combination of a band for insertion within the fold of the shirt collar; a second band for insertion within the collar, provided with a notch; and a U-shaped band, having one of its 45 legs extending from the first band, its bight received in said notch, and its other leg disposed against said second band.

WALTER C. KROUT
